UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,947, dated June 24, 1890.

Application filed April 15, 1890. Serial No. 348,106. Term of patent 3½ years.

To all whom it may concern:

Be it known that I, HENRY O. SCHMIDT, a citizen of the United States, residing in New York, in the county and State of New York, ⁵ have invented and produced a new and original Design for Cane or Umbrella Handles, of which the following is a specification, reference being had to the accompanying drawing, forming part thereof.

The drawing illustrates a side elevation of a cane or umbrella handle embodying my new design, in which A is the lower part of the handle, surmounting the base-rings F and branching at the upper part into the short ¹⁰ shank C and the long shank B. These parts A, B, and C are formed with longitudinal ribs, as shown, which may be of plain or shaded metal, and said ribs are made to branch or

run into each other. The ends E of the shanks or parts B and C may be plain. At intervals, ²⁰ over the parts A, B, and C are disposed ornamental flower designs D. The base F is an annular band or bands.

The handle is made of any suitable material. ²⁵

Having now described my new design, what I claim as new, and desire to secure by Letters Patent, is—

The design for umbrella or cane handles, substantially as herein described and shown. ³⁰

In testimony of which invention I have hereunto set my hand.

HENRY O. SCHMIDT.
